US0D1040793S

(12) **United States Design Patent** (10) Patent No.: **US D1,040,793 S**
(45) Date of Patent: ** Sep. 3, 2024

(54) **PHONE CASE WITH CAMERA LENS MOUNT**

(71) Applicant: **Sandmarc, LLC**, San Diego, CA (US)

(72) Inventor: **Abel Tadesse**, San Diego, CA (US)

(73) Assignee: **Sandmarc, LLC**, San Diego, CA (US)

(**) Term: **15 Years**

(21) Appl. No.: **29/851,493**

(22) Filed: **Aug. 29, 2022**

(51) LOC (14) Cl. **03-01**

(52) U.S. Cl.

USPC **D14/250**

Primary Examiner — L. A. Grabenstetter

(57) **CLAIM**

The ornamental design for a phone case with camera lens mount, as shown and described.

DESCRIPTION

FIG. 1 is a rear perspective view of a phone case with camera lens mount showing my new design;

FIG. 2 is a front view of the phone case with camera lens mount of FIG. 1;

FIG. 3 is a rear view of the phone case with camera lens mount of FIG. 1;

FIG. 4 is a right side view of the phone case with camera lens mount of FIG. 1;

FIG. 5 is a left side view of the phone case with camera lens mount of FIG. 1;

FIG. 6 is a top view of the phone case with camera lens mount of FIG. 1; and,

FIG. 7 is a bottom view of the phone case with camera lens mount of FIG. 1.

1 Claim, 6 Drawing Sheets
